UNITED STATES PATENT OFFICE

136,887

DESIGN FOR A TEXTILE FABRIC OR THE LIKE

Henry Fleischman, New York, N. Y.

Application September 28, 1943, Serial No. 111,229

Term of patent 3½ years

To all whom it may concern:

Be it known that I, Henry Fleischman, a citizen of Hungary, residing at New York city, county of New York and State of New York, have invented a new, original, and ornamental Design for a Textile Fabric or the like, of which the following is a specification, reference being had to the accompanying drawing, forming part thereof.

The figure in the drawing is a plan view of a textile fabric or the like embodying my design.

I claim:

The ornamental design for a textile fabric or the like, substantially as shown.

HENRY FLEISCHMAN,
